METHOD OF MAKING SCORE LINES

Wilfred E. Burns, Burlingame, Calif., assignor to
M. J. B. Company

Application June 1, 1931, Serial No. 541,241

3 Claims. (Cl. 113—15)

This invention relates to improvements in tearing strip cans or containers, and it has reference more particularly to a method of and means for forming the scored lines whereby the tearing strip is defined; it being the principal object of the invention to form scored lines that are free of all imperfections that are caused or might be caused by use of defective scoring rolls.

10 Explanatory to the invention, it will be stated that, it is the common practice to score the can body blanks prior to their being formed into the body, and this is done by passing the blank beneath two sharpened rolls which are pressed 15 thereagainst to cut parallel grooves in the blank, thereby setting off the tearing strip. This method of scoring is satisfactory only so long as the scoring rolls are free of all imperfections in their cutting edges which might operate to destroy 20 the integrity or continuity of the score lines. It is a fact that a nick in the edge of a cutting roll, even so fine as to be undiscernible to the eye or touch, will cause a blank spot in the line of scoring which will be sufficient to permit or 25 cause the tear, when the strip is being removed, to depart from the scored line and thus cause the strip to break or run out. Also, brittleness or hard spots in the tin plate will cause the rolls to jump in passing over them and this like- 30 wise operates to cause blank spots in the line of scoring which are detrimental to proper removal of the tearing strip in that they cause it to run out or break.

The undesirable running out or breaking of the 35 tearing strip has been offset to a certain extent, by the employment of what is termed "herring-bone scoring" consisting of score lines placed at close intervals within the boundary lines of the strip and directed angularly into the boundary 40 lines in the direction of tearing so that, should a tear break away from the boundary line, it will be caught by one of the angular lines and be directed back into its proper channel.

Another method of scoring has been to pro- 45 vide an outer set and an inner set of parallel score lines, the strip normally being removed along the outer score lines, but should the tear break away from the outer lines it will be carried on by the inner ones.

50 The present invention differs from the first of these prior methods in that it does not seek to return a tear back to the scoring should it break from it, but on the contrary, it provides a method of scoring whereby all imperfections in the scor- 55 ing, by reason of defective rolls or hard spots

in the tin plate, will be eliminated and score lines will be formed in a manner and of a character that will allow of no tendency for the tears, formed in removal of the strip, to leave them.

The present invention differs from the above 60 mentioned and previously used method of parallel scoring in that it does not seek to provide supplemental scoring lines to carry the strip in the event of the tear leaving the main line, but to insure the integrity and continuity of the main 65 68 lines of scoring.

More specifically stated, the objects of the present invention are attained by the use, in forming the score lines, of scoring rolls arranged in tandem; the second set following the path 70 of the first set so that any imperfection in the lines cut by the first rolls, will be corrected by the second set of rolls.

The invention contemplates also that the first set of scoring rolls might be relatively heavy so 75 as to operate to clear a path for the second set which could be sharper and set slightly deeper.

The invention further contemplates setting the first and second rolls in a manner to provide two cuts very close instead of coincident to each other, 80 thereby to weaken the metal so that the tear will follow without breaking out.

Other objects of the invention reside in the de- 85 tails of construction, combination of parts and manner of forming the scoring lines, as will here- inafter be fully described.

In accomplishing these and other objects, I have provided the improved details of construction, the preferred forms of which are illustrated in the 90 accompanying drawing wherein—

Fig. 1 is a view of a can body blank, showing the formation of the scoring to set off a tearing strip.

Fig. 2 is a side view illustrating the arrangement of the scoring rolls.

Fig. 3 is a plan view of the same.

Figs. 4 and 5 respectively are enlarged cross sectional views showing the formation of the scoring by the first and second sets of rolls.

Fig. 6 is a view illustrating the formation of 100 score lines by the first and second rolls set just slightly offset one from the other.

Referring more in detail to the drawing—

1 designates what may be the usual tin plate 105 blank from which a can body may be formed, and 2 and 3 designate the parallel lines of scoring setting off a removable tearing strip 4 which, as seen in Fig. 1, terminates at one end in a tongue 5 to which a key may be applied to wind 110

up and remove the strip to open the can after it has been seated.

In carrying out the scoring operation in accordance with the present invention, I provide 5 two sets of scoring rolls, as seen in Figs. 2 and 3. The first set of rolls 6-6 are carried by a shaft 7 rotatable in bearing blocks 8. The second of rolls 9-9 are carried by a shaft 10 rotatable in bearings 11. The bearings 8 and 11 are 10 mounted adjustably in a block 12 and set screws 13 adjust them to gauge the depth of the cut to be made in the tin plate as it is passed beneath them. It will be stated here that any of the usual methods of mounting the scoring rolls and 15 of feeding the tin blanks beneath them might be employed, and it is not the intention of applicant to make any claims to details in this respect.

The gist of this invention resides in the arrangement of the second set of rolls to follow exactly 20 within the path cut by the first set, or to follow so closely thereto as to form parallel lines and to break the metal in the intervening space so that they are, in effect, the same line.

25 In Fig. 3, I have shown the second set of rolls arranged to follow exactly in the path of the first set of rolls. When so arranged, it is quite obvious that any imperfection of the cuts formed by the first set, such as might be caused by a nick

30 in a cutting edge, will be corrected by the following roll in the second set since it would be very unlikely that there might be any nick in the second roll which would coincide with that in the first set.

35 In Figures 4 and 5 I have illustrated the formation of the score lines by first and second rolls that are slightly different in construction; the second of the first set having cutting edges that are rather blunt, as seen at 15. These cutting

40 edges define the groove and break a path for the cutting edges of the second set of rolls. The cutting edges of the second set of rolls, as seen at 16 in Fig. 5, are quite sharp, and they are narrower

45 and are set somewhat deeper than those of the first set, so as to make a clean cut along the base of each groove formed by the rolls of the first set. In this arrangement the first rolls bear the

50 free of strain.

In Fig. 6 I have shown scoring formed by the two sets of rolls set slightly offset so as to form

scored lines 17-18 very close to each other as distinguished from their being coincident. In this arrangement the lines are so close together that the tin plate is so broken or weakened between them that they are, in effect, the same as coincident lines.

The advantages of so scoring the blank is that score lines free of imperfections, resultant to defective cutting edges of the rolls, hard spots or brittleness in the tin plate, are eliminated, and, in removal of the tearing strip, the tears will follow the lines of scoring without tendency of breaking away. Furthermore, the herringbone scoring is not required, as a safeguard to removal of the strip. However, it will be mentioned that the herringbone scoring might still be used if it is desired.

While it is not absolutely essential that the cutting edges of the first set of rolls be wider and relatively blunt as compared to the second set, this is desirable as it provides for use of substantial rolls for initially breaking the metal, to clear the way for the second set, and it provides for use of a second set that can be relatively sharp to form a clean cut groove.

If the rolls are set in a manner to provide the parallel grooves as seen in Fig. 6, it would be preferable that both sets be the same and designed to cut to the same depth.

Having thus described my invention, what I claim as new therein and desire to secure by Letters Patent, is—

1. The method of scoring a can body blank to set off a tearing strip therein which comprises successively impressing coincident grooves in the body blank, each of which decreases its thickness

110 and the first of which is relatively wide, to break the grain of the metal along the boundaries of the second line.

2. A method of scoring metal blanks which comprises impressing a groove of substantial width partly through the blank, then impressing a relatively narrow groove within the base of the

115 first groove.

3. A method of scoring metal blanks which comprises breaking the grain of the metal along a line of substantial width by impressing a groove

120 partly through the blank, then impressing a relatively narrow groove centrally within the base of the first formed groove.
